UNITED STATES PATENT OFFICE.

JACOB E. WISTER AND GEORGE T. TOWNSLEY, OF PHILADELPHIA,
PENNSYLVANIA.

DEVICE FOR FILLING BOTTLES.

No. 813,761.

Specification of Letters Patent.

Patented Feb. 27, 1906.

Application filed January 30, 1905. Serial No. 243,177.

To all whom it may concern:

Be it known that we, JACOB E. WISTER and GEORGE T. TOWNSLEY, citizens of the United States, residing at Philadelphia, in the county of Philadelphia and State of Pennsylvania, have invented new and useful Improvements in Devices for Filling Bottles, of which the following is a specification.

This invention relates to improvements in devices for filling bottles, &c., with medicines or other liquids, and has particular reference to a device for automatically measuring and filling into a bottle a predetermined quantity of liquid.

The invention consists in the novel construction, arrangement, and combination of the several parts of the device, as hereinafter described, illustrated in the drawings, and more particularly pointed out in the claims hereunto appended.

It is a well-known fact to bottlers of medicines and other expensive liquids that bottles designed to be of the same size vary materially in the quantity they hold. For this reason it is very desirable to have a device whereby the exact quantity will be measured, and filled into each bottle. In the bottling of medicines, expensive or otherwise, it has heretofore been the custom to fill the bottle full, although it may hold a quantity greater than designed, which in the case of an expensive liquid frequently results in a loss to the bottler. To avoid this difficulty, the present device has been designed by means of which the exact predetermined quantity is measured and filled into each bottle.

In the drawings, Figure 1 is a side elevation of the improved bottle-filling device; and Fig. 2 is a front elevation, partly in section and partly broken away, showing the construction of the measuring-receptacles, their connection with the supply-tank, and mechanisms for controlling the admission of the liquid to and exit therefrom.

Referring to the drawings, the numeral 1 indicates a suitable tank or reservoir for the liquid to be measured and bottled and is supported on standards 2 2 on a suitable platform 3. This platform is mounted on casters 50 or rollers 4 4, so that it may be moved from place to place as desired. The bottom of the tank or reservoir 1 is provided with two or more openings 5 5, into which are set and se-

cured short pipes 6 6, preferably larger at the bottom than at the top.

7 7 are vertically-depend ing rods secured to the bottom of the tank to each side of the openings 5 5, and a short distance therefrom, the lower ends of said rods being screw-threaded for the purpose of receiving suitable 60 taps or nuts 8 8.

The numeral 9 indicates the fluid-measuring receptacle and is constructed to hold a predetermined quantity of liquid. This receptacle 9 consists of a plate 10, having an opening 11 therein for the passage of the liquid from the pipe 6 into said receptacle, and air-vents 12 and 13; a plate 14, having a depressed center 15, preferably the shape of an inverted frustum of a cone, the bottom thereof being contracted and provided with an opening 16 to permit the liquid to pass from said receptacle, said contracted portion terminating in a tube 17, sufficiently small to enter the mouth of a bottle to be filled; a casing 18, preferably 75 of glass, interposed between the plates 10 and 14; a tube 19, attached to the under side of the plate 10, around the opening 11 and extending a sufficient distance down into the measuring-receptacle to prevent the liquid 80 foaming or frothing as it enters the receptacle; a valve 20, adapted to close the opening 16 in the plate 14; a float-valve 21, adapted to close the vent 12, and valves 22 and 23, adapted to close the opening 11 and the vent 13, respectively, for a purpose hereinafter stated. This measuring-receptacle 9 is held against the bottom of the pipe 6 or the bottom of the tank 1, as desired, by means of the rods 7 7 and taps or nuts 8 8, as is apparent. The 90 float-valve 21 is raised by the liquid flowing into the receptacle, and by reason of the construction of this valve, as shown in the drawings, the vent 12 is closed thereby before the receptacle is completely filled, and there 95 would ordinarily remain in said receptacle a quantity of air above said liquid. In order to avoid this condition and to permit the complete filling of the receptacle, the valve 13 is provided, whereby the air remaining in the receptacle after the closing of the vent 12 is permitted to escape and the receptacle 100 completely filled.

Secured to the plate 14 of each measuring-receptacle is a fulcrum 24. Hinged or fulcrummed on each of these fulcrums is a lever

25 26, having one end 27 thereof preferably bifurcated and attached to an annular sliding collar 28 on the tube 17 and connected with a valve 20, through a vertical slot 29 in said 5 tube by stem 30, as shown.

The numeral 31 indicates a tube having its lower end over the vent 13 and extending upward either through the tank or to the outside thereof beyond the top of said tank and 10 is primarily for the purpose of receiving and holding the overflow occurring after the filling of the receptacle 9 and before the closing of the inlet or opening 11 of said receptacle.

15 32 indicates the stem of the valve 23, located within the tube 31.

33 indicates the stem of the valve 22 and extends up through the tube 6 and the tank or reservoir and beyond the top thereof and is rigidly connected with the valve-stem 32 by 20 a link 34 in any suitable manner.

The numerals 35 and 36 indicate suitable standards secured to the tank and have fulcrumed or hinged to the upper ends thereof the levers 37 and 38, respectively. These levers 25 37 38 are each connected with one of the links 34, as is evident. The opposite end of the lever 37 is connected with the free end of the lever 25 by the rod 39, and the lever 26 is connected with the lever 38 by the rod 40, as 30 shown, for a purpose hereinafter stated.

The numeral 41 indicates a suitable vertically-movable bottle seat or holder which is fulcrumed or hinged upon one end of a lever 42, the opposite end of said lever being provided with an adjustable counterbalance-weight 43. This bottle-holder is located directly beneath the tube 17 and is for the purpose of receiving a bottle and holding the same in position to be filled, holding the bottle in such position that the end of the tube 17 will project down into the mouth thereof.

The sliding collar 28 on each of the tubes 17 is sufficiently heavy to hold the valve 20 in the bottom of each receptacle closed and at 45 the same time hold the valves 22 and 23 at the top of the opposite receptacle closed, so that when one receptacle is being emptied the opposite one will be filling.

The operation of the device is as follows: 50 The bottle to be filled is placed on the bottle-holder 41 and the tube 17 inserted into the mouth thereof. The weight on the opposite end of the counterbalance-lever 42 will raise the mouth of the bottle into contact with the sliding collar 28 and raise the same and the valve 20, connected therewith, and permit the liquid in the receptacle to flow into the bottle, as is evident. When this receptacle has been emptied, the bottle is removed, where- 55 60 upon the sliding collar 28 will return to its normal position, closing the valve 28, connected therewith, and also the valves 22 and 23 at the top of the opposite receptacle and permit no more liquid to enter therein. A bottle is 65 then placed in position under this filled re-

ceptacle and raised, lifting the sliding collar 28 on the tube 17 of this receptacle and permitting the liquid to flow therefrom into the bottle. The raising of the collar 28 will throw the opposite end of the lever to which it is attached down and through its connections open the valves 22 and 23 at the top of the opposite receptacle and permit liquid to flow from the tank into said receptacle. This operation may be carried on indefinitely and 75 bottles filled alternately from each receptacle.

Instead of having two measuring-receptacles, as herein shown, the number may be increased as desired, as will be evident.

The quantities measured by this device 80 may be varied by changing the size of the casing 18, as is evident, or by any other suitable means, and we do not, therefore, desire to confine ourselves to the precise structure herein shown.

Having thus fully described our invention, what we claim, and desire to secure by Letters Patent of the United States, is—

1. In a device of the character described, the combination with a tank or reservoir, 90 measuring-receptacles connected therewith, and an inlet-valve and an outlet-valve in each receptacle, of independently-operated mechanisms attached to each of said receptacles, the mechanism attached to one receptacle being connected with the outlet-valve of such receptacle and with the inlet-valve of another receptacle, and adapted when said outlet-valve of one receptacle is opened to automatically cause the inlet-valve, with 100 which it is connected, of the other receptacle to open, and which upon the closing of said outlet-valve will automatically cause the inlet-valve, with which it is connected, to close.

2. In a device of the character described, 105 the combination with a tank or reservoir, and measuring-receptacles connected therewith, each of said receptacles having an air-vent and an inlet-opening in its top, and a contracted bottom terminating in a tube, a 110 valve normally seated in the bottom over the tube, and a sliding collar on the tube of each receptacle connected with said valve, and a series of levers connecting the sliding collar of one receptacle with an air-vent and an inlet- 115 opening of the opposite receptacle, and a weighted bottle-holder located beneath each of said tubes, whereby when a bottle is seated on said bottle-holder it will be raised automatically into contact with the sliding collar, 120 raising the same and opening the outlet-valve of the receptacle, and at the same time, through the connecting-levers, automatically open the inlet and air-vent of the opposite receptacle.

3. In a device of the character described, the combination with a tank or reservoir, measuring-receptacles connected therewith and adapted to hold a predetermined quantity, and an inlet and outlet, and valves 130

therefor, for each receptacle, of means adapted to be operated by the placing in position of a vessel beneath one of the receptacles to automatically open the outlet-valve of one receptacle, and mechanism connected therewith and operated thereby whereby the inlet-valve of an opposite receptacle is opened.

4. In a device of the character described, the combination with a tank or reservoir, measuring-receptacles connected therewith, an inlet and an outlet, and valves therefor, in each receptacle, of a valve opening and closing means at the lower end of each receptacle and connected with the outlet-valve thereof, and mechanism connecting said valve opening and closing means with the inlet-valve of an opposite receptacle, whereby said valve opening and closing means will, when actuated by the placing in position of a vessel beneath one of the receptacles, open the outlet-valve of such receptacle and at the same time automatically open the inlet-valve of the opposite receptacle, whereby when one receptacle is being emptied the other one is being filled.

5. In a device of the character described, the combination with a tank or reservoir, measuring-receptacles connected therewith, an inlet and an outlet, and valves therefor, and a float-valve for each receptacle, of a valve-actuating mechanism at the lower end of each receptacle, and means connecting said valve-actuating mechanism with the inlet-valve of the opposite receptacle, whereby when the outlet-valve of one receptacle is opened by the placing in position of a vessel beneath one of the receptacles the inlet-valve of the opposite receptacle will be automatically opened

thereby, to permit the filling of one receptacle while the other receptacle is being emptied.

6. In a device of the character described, the combination with a tank or reservoir, measuring-receptacles connected therewith, an inlet and an outlet, and valves therefor, and two air-vents and valves therefor for each receptacle, of a valve-actuating device at the bottom of each receptacle connected with the outlet-valve of such receptacle and also with the inlet-valve of the opposite receptacle by a series of levers, whereby when said valve-actuating device at the bottom of one receptacle is operated to open the outlet-valve of such receptacle by the placing in position of a vessel to receive the contents of such receptacle, the inlet-valve of the opposite receptacle will be automatically opened thereby.

7. In a device of the character described, the combination with a tank or reservoir, a measuring-receptacle connected therewith, an inlet and an outlet and suitable valves therefor, and two vents and a valve for each vent; of an overflow-tube over one of said vents, said tube being adapted to receive and hold the overflow from said receptacle occurring after the filling of such receptacle and before the closing of the inlet thereof.

In testimony whereof we affix our signatures in presence of two subscribing witnesses.
